STOCKING

Frank J. Kros, Philadelphia, Pa.

Application April 1, 1953, Serial No. 24,300

Term of patent 14 years

(Cl. D47—7)

FIG. 1

FIG. 3

FIG. 2

Fig. 1 is a side elevational view of a stocking showing my new design.

Fig. 2 is a fragmentary front elevational view thereof, and

Fig. 3 is a fragmentary rear elevational view thereof.

The patches of shading on the leg and ankle portions indicate the continuous sheerer portions of the stocking.

I claim:

The ornamental design for a stocking, as shown and described.
